UNITED STATES PATENT OFFICE.

JOHN R. FOSTER, OF ARLINGTON, MASSACHUSETTS.

DESIGN FOR A FRAME FOR PICTURES, MIRRORS, OR SIMILAR ARTICLES.

40,994.

Specification for Design.

Patented Nov. 22, 1910.

Application filed September 12, 1910. Serial No. 581,739. Term of patent 3½ years.

To all whom it may concern:

Be it known that I, JOHN R. FOSTER, a citizen of the United States, residing at Arlington, in the county of Middlesex and Commonwealth of Massachusetts, have invented a new, original, and ornamental Design for a Frame for Pictures, Mirrors, or Similar Articles, of which the following is a specification, reference being had to the accompanying drawing, forming part thereof.

The figure in the drawing is a front elevation of a frame showing my new and original ornamental design.

I claim:

The ornamental design for a frame for pictures, mirrors, and similar articles as shown.

In testimony whereof, I have signed my name to this specification, in the presence of two subscribing witnesses.

JOHN R. FOSTER.
